UNITED STATES PATENT OFFICE.

RICHARD LUNDQUIST, OF LAGUNA DE TERMINOS, MEXICO.

ROTARY ENGINE.

No. 883,034.

Specification of Letters Patent. Patented March 24, 1908.

Application filed December 24, 1907. Serial No. 407,894.

To all whom it may concern:

Be it known that I, RICHARD LUNDQUIST, a subject of the King of Sweden, and a resident of Laguna de Terminos, Campeche, Mexico, have invented a new and Improved Rotary Engine, of which the following is a full, clear, and exact description.

This invention relates to certain improvements in rotary engines adapted to be operated by steam, compressed air, or any other suitable motive fluid under pressure, and the object of the invention is to provide certain improved mechanism whereby the engine may be more readily controlled and rotated in either direction at will.

The invention consists in certain features of construction and combinations of parts, all of which will be fully set forth hereinafter and particularly pointed out in the claims.

Reference is to be had to the accompanying drawings, forming a part of this specification, in which similar characters of reference indicate corresponding parts in all the figures, and in which

Fig. 1 is an end view of an engine constructed in accordance with my invention; Fig. 2 is a transverse section; Fig. 3 is a longitudinal section taken on the line 3—3 of Fig. 2; Fig. 4 is a side view of the rotor; Fig. 5 is a perspective view of a section of a portion of the rotor; Fig. 6 is a longitudinal section through the controlling valve; and Fig. 7 is a perspective view of the valve plug.

In my improved engine I employ any suitable form of casing 10 having a cylindrical chamber therein and supported in any suitable manner, as, for instance, upon base blocks 11. Within the cylindrical chamber of the casing there is provided a rotary member or rotor secured to the main drive shaft 12 and adapted to be operated by a motive fluid admitted through suitable inlet ports and escaping through suitable exhaust ports. The rotor is so constructed and the inlet and exhaust ports are so disposed, that the said rotor may be caused to rotate in either direction desired. The rotor preferably comprises a cylinder 13 somewhat smaller than the cylindrical chamber of the casing and having a plurality of circumferential flanges 14 extending outward toward the casing wall but spaced a very short distance therefrom. Any number of these circumferential flanges may be employed, but preferably they subdivide the space between the surface of the cylinder and the surrounding casing into an

even number of annular chambers. Within each of these annular chambers there are disposed baffle plates 15, the baffle plates in each alternate annular space being constructed to bring about rotation in one direction, while the baffle plates in the remaining annular chambers are constructed to bring about rotation in the opposite direction. The annular rings 14 and the baffle plates 15 may be constructed and secured in place in any suitable manner, but, as illustrated, a plurality of sleeves 16 are bolted to the cylinder 13, each sleeve carrying one of the rings 14 and one annular row of baffle plates 15. In Fig. 5, I have illustrated two of these rings disposed adjacent each other and illustrating more clearly the shape of the baffles and the difference in the arrangement of baffles in adjacent rows.

For admitting the motive fluid to the casing, there are provided two separate sets of inlet ports upon each side and constructed to be controlled by valves, whereby motive fluid may be admitted through either of the sets upon each side. As illustrated, valve casings 17 are bolted to the main engine casing 10, and from each valve casing there are curved inlet passages 18 tapering in form and terminating in discharge nozzles 19 entering each alternate annular chamber substantially tangentially thereof, while for each valve casing there are also provided curved tapered passages 18^a (shown in dotted lines in Fig. 2) terminating in discharge nozzles 19 entering the remaining annular chambers in the opposite direction and also substantially tangentially. The passages 18 on one side leading from one valve casing, admit to the same annular chambers as do the inlet passages upon the opposite side, and both admit at such an angle as to cause rotation in the same direction; while the passages 18^a on one side admit to the same chambers as do the passages 18^a upon the opposite side, and these admit to the remaining annular chambers and cause rotation of the cylinder in the opposite direction.

For controlling the admission of motive fluid through the passages, there are provided hollow substantially cylindrical valves 26, one of which is illustrated in Fig. 7. These valves receive motive fluid at the interior thereof from suitable inlet pipes 21, and the valves are provided with ports through which the motive fluid may escape into the passages 18 or 18^a, but so disposed that mo-
